UNITED STATES PATENT OFFICE

143,239

DESIGN FOR A PIPE THREADING TOOL

William A. Phillis, Warren, Ohio, assignor to
Beaver Pipe Tools, Inc., Warren, Ohio, a cor-
poration of Ohio

Application June 30, 1945, Serial No. 120,438

Term of patent 14 years

(Cl. D54—13)

To all whom it may concern:

Be it known that I, William A. Phillis, a citizen
of the United States of America, residing at War-
ren, county of Trumbull, State of Ohio, have in-
vented a new, original, and ornamental Design
for a Pipe Threading Tool, of which the follow-
ing is a specification, reference being had to the
accompanying drawings, forming a part thereof.

In the drawings, Fig. 1 is a perspective view

looking at the front and left side of a pipe thread-
ing tool embodying this new design; Fig. 2 is a
perspective view looking downwardly at the right
side and front of such tool; Fig. 3 is an elevation
of the tool looking at the left hand face.

I claim:

The ornamental design for a pipe threading
tool, as shown.

WILLIAM A. PHILLIS.
